UNITED STATES PATENT OFFICE

SIMON COOPER, OF BROOKLYN, NEW YORK, ASSIGNOR TO COOPER TEA PACKET COMPANY, OF BROOKLYN, NEW YORK, A CORPORATION OF NEW YORK

PACKET-PACKAGE AND DISPENSING APPARATUS

Application filed April 3, 1929. Serial No. 352,154.

My invention relates to apparatus for advantageously dispensing small articles or packets such as tea packets (sometimes known as tea balls or tea bags), and to a novel package, or arrangement of a plurality of the packets, for dispensing from the apparatus.

The general object is to permit the user, such as an attendant in a restaurant, to conveniently and quickly take one tea bag from the supply without annoyance caused by entangling of the string with the other packets or packet strings, and also to arrange the bags in an orderly manner in a compact package which is designed for easy placement in the dispenser and to cooperate with the same for the convenient extraction of individual packets.

The characteristics and advantages of the invention are further sufficiently explained in connection with the following detail description of the accompanying drawings, which shows one representative embodiment. After considering this example, skilled persons will understand that many variations may be made without departing from the principles disclosed, and I contemplate the employment of any structures that are properly within the scope of the appended claims.

In the drawings:

Fig. 1 is a section at 1—1, Fig. 2 of a vertical section of dispensing apparatus and of packet-package or roll embodying the invention in one form.

Fig. 2 is a right-hand elevation of Fig. 1.

Fig. 3 is a section at 3—3, Fig. 1.

Fig. 4 is a plan view of one form of packet for use of which the invention is adapted.

While not limited to the precise kind of article or packet to be dispensed, the invention is well adapted for the handling of approximately thin and flat tea packets 1, such as shown in Figs. 1 and 4, these consisting of a cheese-cloth bag containing tea and having attached at a convenient point, such as one corner, a string 2 connected to a tag or label 3. In the ordinary packing and handling of these packets the strings become entangled with other strings or packets and considerable annoyance is occasioned to the user in extracting single packets. The invention

aims to overcome this difficulty in a novel way, and also to provide improved means for packing or packaging a plurality of the bags or tea packets so that the quality of the tea is not impaired and so that the package or roll of packets is easily placed for dispensing in a dispensing container of the character also included in the invention.

To form the dispensing package I provide a core or spool consisting of a cylindrical block 5 which may be wood, centrally bored at 6 (to receive a pin or shaft as later referred to). One end of a paper strip 7 is connected to the periphery of the block, the length of the block and width of the strip substantially corresponding to the width of a packet 1. The strip is then wound or coiled spirally about the block, and at the same time the packets are laid upon the strip and between the turns thereof in a single spiral layer or series, as sufficiently explained in Fig. 1, and the strings and tags may be laid lengthwise in orderly and symmetrical manner over the faces of the adjacent packets so that the strings and tags will not become entangled. The outer end of the paper strip, when the roll is of the desired diameter, may be secured as by gluing or stapling it to the underlying turn of the strip.

A dispensing container adapted for the handling of such rolls or packages comprises a box 10 which may be rectangular and of width equal to the width of the packet roll. The side walls of the box have opposite slots 11 extending down from their upper edges. The box has a cover 12 hingedly connected at 13. A shaft 14 is provided to slip easily into the bore 6 of block 5. Near its ends the shaft has annular grooves 15 to cooperate with the edges of the box wall slots so that after the shaft is inserted in the block or core of a package the shaft grooves are engaged with the box slots and thereafter the package or roll is revolvably located within the box and descends by gravity during dispensing, as further explained, and the shaft is restrained from displacement until removed from the box.

The periphery of the roll or package engages with a curved support or friction plate

16 pivotally mounted on a pin 17, the ends of which are set in the box side walls. From the pin or pivot point of plate 16 a fixed plate or shelf 18 extends to the front wall 5 19 of the box at the lower edge of a discharge aperture 20 therein. A spring, such as the wire spring or springs 21, connected to or about the pin 17, engage plate 16 and urge it yieldingly upward. Severing means for 10 the paper strip may be provided at the lower edge of the aperture, conveniently by forming the outer end of plate 18 as a knife edge 22. The lower part of the box serves as a receptacle for the waste paper strip, and the 15 front wall has an aperture 23 giving access to this receptacle.

In operation, after a package or roll of the tea packets has been placed in the box in the manner above explained, its lower and rear 20 peripheral portion rests on the friction plate 16. The roll is so placed that the end of the paper strip is directed toward the front of the box and before placing in the box the end of the strip is freed and is brought out 25 over ledge 18 through door or aperture 20. Then by grasping the end of the strip the roll is rotated and the individual packets are freed from the roll and drawn forward to the opening, whereupon their strings and 30 tags are presented for easy grasping and the packets may be removed singly as desired, without entanglement or other interference with the remaining packets. The strip as drawn off may be passed into the lower receptacle by inserting it through aperture 23, either before or after severing the strip. It 35 may easily be severed as desired by tearing upon the knife edge 22. As packets are removed the roll decreases in diameter and 40 descends by gravity, with pin or shaft 14 descending through the wall slots 11 and keeping the roll properly centered for rotation until it is exhausted, whereupon pin and core 45 are removed and another roll of packets inserted.

I claim:

1. Dispensing apparatus for purposes described, comprising a box adapted to receive 50 a packet roll, an arcuate friction plate to receive the periphery of a roll strip, and a shelf extending from said plate to a discharge aperture, said plate being pivotally mounted, means urging it to frictional engagement with the roll, and a shelf extending from said plate 55 to a discharge aperture.

2. A dispensing apparatus for the purposes described comprising a box adapted to receive a packet roll, vertical guides to receive a roll shaft, an arcuate friction plate to receive 60 the periphery of a roll strip, said plate being pivotally mounted, means urging it to frictional engagement with the roll, and a shelf extending from said plate to a discharge aperture.

65 3. A dispensing container comprising a

box having at opposite sides substantially vertical shaft guides and having in a front wall a discharge opening, a strip-and-packet-supporting shelf leading from a point approximately below the guides to said discharge opening, an arcuate friction plate pivotally connected adjacent the inward end of the shelf, and means uniformly urging the friction plate generally upward and toward the guides. 75

4. A dispensing container comprising a box having at opposite sides substantially vertical shaft guides and having in a front wall a discharge opening, a strip-and-packet-supporting shelf leading from a point approximately below the guides to said discharge opening, an arcuate friction plate pivotally connected adjacent the inward end of the shelf, means uniformly urging the friction plate generally upward and toward 80 the guides, the box being adapted to receive a dispensing package of flat circular form comprising a core, a retaining and feed strip of sheet material connected to the core and wound spirally about it and substantially 85 thin and flat commodity packets orderly arranged in spiral row formation between the turns of the strip, the shelf and friction plate being adapted to support the package by engagement with the strip forming its periphery, the guides being adapted to receive a shaft passing through the package core, and the friction plate being adapted to engage the package periphery as the package descends 90 by gravity while its diameter diminishes during dispensing and apply friction to maintain proper feed tension and retain the packets in their orderly positions. 95

5. A dispensing container comprising a box having at opposite sides substantially vertical shaft guides and having in a front wall a discharge opening, a strip-and-packet-supporting shelf leading from a point approximately below the guides to said discharge opening, an arcuate friction plate pivotally connected adjacent the inward end of the shelf, means uniformly urging the friction plate generally upward and toward the guides, in combination with a dispensing package of flat circular form comprising a core, a retaining and feed strip of sheet material connected to the core and wound spirally about it and substantially thin and flat commodity packets orderly arranged in spiral row formation between the turns of the strip, the shelf and friction plate being adapted to support the package by engagement with the strip forming its periphery, the guides being adapted to receive a shaft 110 passing through the package core, and the friction plate being adapted to engage the package periphery as the package descends 115 by gravity while its diameter diminishes during dispensing and apply friction to main- 120

tain proper feed tension and retain the packets in their orderly positions.

6. A dispensing container comprising a box having at opposite sides substantially vertical shaft guides and having in a front wall a discharge opening, a strip-and-packet-supporting shelf leading from a point approximately below the guides to said discharge opening, an arcuate friction plate 10 pivotally connected adjacent the inward end of the shelf, means uniformly urging the friction plate generally upward and toward the guides, in combination with a dispensing package of flat circular form comprising a core, a retaining and feed strip of sheet material connected to the core and wound spirally about it and substantially thin and flat commodity packets orderly arranged in spiral row formation between the turns of the strip, the packets having attached thereto 20 strings and tags, directed forward with relation to the direction of package rotation during dispensing, the shelf and friction plate being adapted to support the package by engagement with the strip forming its periphery, the guides being adapted to receive a shaft passing through the package core, and the friction plate being adapted to engage the package periphery as the package descends 30 by gravity while its diameter diminishes during dispensing and apply friction to maintain proper feed tension and retain the packets in their orderly positions.

7. A dispensing container comprising a box 35 having at opposite sides substantially vertical shaft guides and having in a front wall a discharge opening, a strip-and-packet-supporting shelf leading from a point approximately below the guides to said discharge opening, an arcuate friction plate pivotally connected adjacent the inward end of the shelf, means uniformly urging the friction plate generally upward and toward the guides, the box being adapted to receive a dispensing package of flat circular form comprising a core, a retaining and feed strip of sheet material connected to the core and wound spirally about it and substantially thin and flat commodity packets orderly arranged 45 in spiral row formation between the turns of the strip, the shelf and friction plate being adapted to support the package by engagement with the strip forming its periphery, the guides being adapted to receive a shaft passing through the package core, and the friction plate being adapted to engage the package periphery as the package descends by gravity while its diameter diminishes during dispensing and apply friction to maintain proper feed tension and retain the packets in their orderly positions, the structure and arrangement being such 55 that as the strip is pulled through the discharge opening the packets are presented thereon successively on the shelf at the dis-

charge opening with the tags and strings in forward position for easy grasping and removal of each packet without disturbance of others.

8. A dispensing container comprising a box having at opposite sides substantially vertical shaft guides and having in a front wall a discharge opening, a strip-and-packet-supporting shelf leading from a point approximately below the guides to said discharge opening, an arcuate friction plate pivotally connected adjacent the inward end of the shelf, and means uniformly urging the friction plate generally upward and toward the guides, the box below the shaft and friction plate being dimensioned to provide a container for waste strip portions and the front box wall having an opening below said discharge opening for insertion of the strip or strip portions.

9. A dispensing container comprising a box having at opposite sides substantially vertical shaft guides and having in a front wall a discharge opening, a strip-and-packet-supporting shelf leading from a point approximately below the guides to said discharge opening, an arcuate friction plate pivotally connected adjacent the inward end of the shelf, means uniformly urging the friction plate generally upward and toward the guides, and a strip severing member at the discharge opening.

10. A dispensing container comprising a box having at opposite sides substantially vertical shaft guides and having in a front wall a discharge opening, a strip-and-packet-supporting shelf leading from a point approximately below the guides to said discharge opening, an arcuate friction plate pivotally connected adjacent the inward end of the shelf, means uniformly urging the friction plate generally upward and toward the guides, and a strip severing member at the lower edge of the discharge opening.

11. A dispensing apparatus for the purpose described comprising a box adapted to receive a packet roll, said box being provided with vertical guides to receive a roll shaft, means resiliently forced against the periphery of the packet roll, movable in response to change of diameter of the roll to prevent substantial distortion of the roll, and said box being provided with an aperture for passage of the roll strip and packets.

In testimony whereof I affix my signature.

SIMON COOPER.
